UNITED STATES PATENT OFFICE.

HOLLIS B. CRUM, OF CHICAGO, ILLINOIS, ASSIGNOR TO RAYMOND C. PENFIELD, OF CHICAGO, ILLINOIS.

BRICK-SETTER WITH SELF-ACTING GRIPPING-FINGERS.

1,221,793.

Specification of Letters Patent.

Patented Apr. 3, 1917.

Application filed March 7, 1912. Serial No. 682,166.

To all whom it may concern:

Be it known that I, HOLLIS B. CRUM, a citizen of the United States, and resident of Chicago, county of Cook, State of Illinois, have invented an Improvement in Brick-Setters with Self-Acting Gripping-Fingers, of which the following description, in connection with the accompanying drawings, is a specification, like letters on the drawings representing like parts.

My present invention relates to improvements in mechanism for lifting and setting bricks, or the like, of the type wherein a series of spaced apart lifting fingers carried by a lifting frame are adapted to be inserted in passages in the basic layer of a brick stack; such basic layer being for this purpose formed of spaced apart lines of bricks, on which the rest of the stack is piled. In an apparatus of this character it is necessary that means be provided for gripping the lines of bricks constituting the bottom layer, so as to lift the same along with and in undisturbed relation to the rest of the stack. A prime object of the invention is to provide a mechanism of this character, wherein each finger by itself contains the necessary provision for laterally expanding to grip the adjacent walls of the basic brick lines with sufficient force to lift the same along with the stack as it is raised, thus dispensing with the elaborate and complicated mechanism heretofore considered necessary for effecting this expanding, gripping action by relatively movable parts of the lifting frame work or otherwise. The illustrative form of the mechanism to be set forth is designed for handling a unit of brick, nine brick long and one deep lengthwise, but it is to be understood that the invention is in no way restricted thereto, since the improved construction is equally applicable to construct a setter for handling units of any desired length and depth, it being only necessary in the latter case that the fingers be lengthened with a duplication of the expanding devices to be explained.

The invention will be better understood from the following detailed description, taken in connection with the accompanying drawings, and will be thereafter pointed out in the appended claims.

Referring to the drawings,

Figure 1 is a front elevation of a brick setter embodying my improvements;

Fig. 2 is a sectional view on line 2-2 of Fig. 1;

Fig. 3 is an enlarged section on line 3-3 of Fig. 1;

Fig. 4 is a transverse section through a finger on line 4-4 of Fig. 3;

Fig. 5 is a similar section on line 5-5 of Fig. 3;

Fig. 6 is a side elevation of a lifting finger with the clamping plate sectioned away;

Fig. 7 is a horizontal section through a lifting finger on line 7-7 of Fig. 6;

Fig. 8 is an elevation of a clamping plate removed;

Fig. 9 is a plan view of the expanding wedge or cam members removed from the bottom of a finger;

Fig. 10 is a partial, longitudinal, central vertical section through a finger wherein a modified form of the invention is employed on the line 10-10 of Fig. 11; and

Fig. 11 is a transverse section through a finger having this modified form of the invention.

The lifting frame may be of any usual or desired form, being shown as provided with the usual horizontally extending finger supporting bar 10, formed with upstanding extensions 11, 12 at either side of its center to which are bolted vertical lifting bars 13 and stiffening straps 14 united at their upper ends, as seen at 15, and having fixed thereto a lifting bar 16 with connections 17 to a crane or other lifting and transferring mechanism. The finger supporting bar 10 is shown as provided with recessed seats at 18 to which are bolted a series of parallel spaced apart fingers 19 extending transversely therefrom, these fingers being of a length determined by the depth of the brick unit which it is desired to handle, and shown as approximately the length of a single brick, the ends of these fingers being provided with rounded points 20, as is usual to facilitate their insertion in the passages between the brick lines.

Referring first to the form of the invention shown in Figs. 3 to 9, each finger comprises a main or body portion 21, opposite side clamping plates 22, 23 and expanding wedge or cam portions 24, 25 fixed at the bottom of the main or body portions 21 of the fingers. The body portions 21 are the parts which are rigidly fixed by bolting or otherwise to the finger supporting bar, as

seen at 26, and the clamping plates 22, 23 extend over these bent in overlapping relation at their tops as seen at 27, and down along the sides thereof to the bottoms of the wedge portions 24. These clamping plates are of relatively thin plate stock and their overlapping top portions 27 are fixed together and to a stiffening plate 28 underneath by rivets 29, or the like. The clamping plates are adapted to slide up and down over the body portions 21 and are normally held at an upward limit of movement by coil springs 30 shown as fitted in sockets 31 in the body portions and guided on pins 32 depending from the tops of the plates. Any suitable arrangement of these springs may be provided, two being shown for each finger positioned at similar distances from the longitudinal center of the finger. Each of the clamping plates 22, 23 has projecting inward therefrom, beneath the body portions 21, brackets 33, 34 in which are mounted rollers 35, 36 engageable with oppositely facing wedge or cam surfaces 37, 38 respectively on the upper portions of the members 24, 25; each clamping plate, as shown, has one of these brackets and wedge engaging rollers toward either end at like distances from its center, and the roller carrying brackets for the opposite plates are preferably arranged side by side on either end portion, as clearly seen in Fig. 3. As best seen in Figs. 3 and 9, the opposite wedge faces 37, 38 for coöperation with each pair of rollers 35, 36 are preferably formed on a bracket adapted to be secured at the bottom of the finger, by bolts or the like as at 39, the bracket member for the inner end of the finger being shown at 40, and that for the outer end of the finger at 41, provided with a rounded prow point 42 to correspond with the corresponding prow point 43 of the rest of the finger. The clamping plates 22, 23 are desirably cut out centrally of their length and at their inner extremity, as seen at 44, to promote the resiliency thereof and make them more adaptable for proper frictional engagement with the bricks, and the outer ends of these plates are likewise cut away at 45 to accommodate the prow point 43 at the outer end of the finger.

It may now be understood that the setter having been placed in operative position for lifting a stack of bricks, with the several fingers inserted in the respective passages of the basic layer, as lifting impulse is applied to the setter frame, the top portions 27 of the clamping plates will first come in contact with the body of the stack above the basic layer and have their upward movement temporarily arrested, while the body portions 21 compress the springs 30 and slide upward relative to the clamping plates. By this action the rollers 35, 36 travel relatively downward along the wedge surfaces

37, 38, thus pressing the plates 22, 23 outward, as seen in dotted lines 35, and spreading them sufficiently to strongly grip the brick lines of the basic layer. It will be understood that the wedge surfaces 37, 38 are formed on a proper incline and the capacity for vertical sliding movement of the plates 22, 23 relative to the body portions 21 is such that the clamping plates will exert the requisite clamping force to insure the lifting of the bottom brick lines along with the rest of the stack because of the pressure exerted thereby on the top portions 27 of the plates.

In the form of the invention shown in Figs. 10 and 11, the clamping plate portions 22', 23' are shown as formed of a single piece of plate stock bent to U-form for embracing the sides of the body portion 21 of the finger, the top 27' being flattened for engagement with the bottom of the main portion of the stack above the basic layer, as in the preceding form. The springs 30' in this form are arranged to seat in the body portion 21' and to press upwardly on the top 27', as before described. In this form of the invention a bottom portion 46 is fixed beneath the body portion of the finger by screw bolts 47 or the like, and this portion has fitted therein central bearings, shown as rollers 48 for engagement with bent plates 49, 50 riveted or otherwise secured at their lower ends to the respective clamping plate portions 22', 23', as seen at 51, the inwardly oppositely extending bends of these plates forming opposite inclines over and in position to be engaged by the rollers 48, as lifting impulse is applied to the body portions of the fingers to move them upward relative to the clamping plates, while the clamping plates have their movement arrested by the resistance of the stack. The upper ends of the bent plates 49, 50 are shown as formed with return bends 52, so that they rest against and have sliding bearing on the clamping plates, thus permitting the resiliency of the bent or wedge plates 49, 50 to be added to that of the clamping plates, and making the gripping action of the plates a still more resilient and self-adapting one.

In each of the forms of the invention described, it is to be noted that each finger has wholly self-contained mechanism for effecting the lateral grip upon the basic layers at the same time that the lift is applied to the main portion of the stack, so that no special construction of finger supporting frame is required, or any coöperative parts or attachments needed thereon. My improved fingers are thus adapted to be applied to any desired form of supporting frame which may be of the greatest simplicity, and any danger of breakage which might occur is limited to the particular finger involved, which can be quickly re-

- placed by a duplicate, without in any way disarranging the rest of the mechanism. It is to be further observed that the expanding mechanism for each finger is completely housed within the expanding plates with absolutely no operative parts exposed to injury and no opportunity for chips or foreign matter to get into the working parts and obstruct them.
- 10 Having described my invention, what I claim as new and desire to secure by Letters Patent is:
1. Brick lifting apparatus of the kind described, comprising a plurality of parallel lifting fingers adapted to be positioned under a stack of brick, each finger having a rigid portion and a top portion yieldingly sustained on said rigid portion and adapted to be self-seating against a brick stack independently of each adjacent finger, pivoted expansible side clamping members carried by each finger and means to expand said side members by the relative movement of the top portion with said rigid portion of the lifting finger.
  2. Brick lifting apparatus of the kind de-
- scribed, comprising a lifting frame with a plurality of spaced-apart, brick-engaging fingers, extending from said frame and adapted to be positioned under a brick stack, 30 each finger including a rigid portion and a top portion, yielding means to sustain said top portion on said rigid portion at a plurality of points, whereby an independent longitudinal and self-seating action of each 35 yielding top portion relatively to its rigid portion is provided, when the apparatus is lifted independently of each adjacent lifting finger, yielding side members carried by said top portion, and means consisting in 40 wedge members to move each expansible side member through the depression of the top portion on its rigid portion during initiation of the brick lifting movement.
- 15 In testimony whereof, I have signed my 45 name to this specification, in the presence of two subscribing witnesses.
- HOLLIS B. CRUM.
